UNITED STATES PATENT OFFICE

2,107,175

HAIR WAVING WRAPPER PAD

Platon Constantine, New York, N. Y.

Application September 1, 1936, Serial No. 98,895

6 Claims. (Cl. 132—36.2)

This invention relates to improvements in hair waving wrapper pad, and this application constitutes a continuation in part of my copending application filed March 31, 1936, Serial No. 71,833 for Hair waving wrapper.

One of the main features of the invention is the provision of an improved hair waving wrapper pad which may be securely held in a position to enclose a wound strand of hair.

Another feature of the invention is to provide a wrapper pad whereby the two longitudinal edges of the pad may be secured together and the joint therebetween tightly sealed to prevent injury to the scalp of a user by the escape of heated vapor from within the pad.

With these and other objects in view, the invention resides in the certain novel construction, combination and arrangement of parts, the essential features of which are hereinafter fully described, are particularly pointed out in the appended claims, and are illustrated in the accompanying drawing, in which:

Figure 1 is a perspective view of the hair wrapper pad in a flat condition.

Figure 2 is an enlarged vertical transverse sectional view on the line 2—2 of Figure 1.

Figure 3 is a vertical transverse sectional view through the wrapper pad illustrating the same in rolled position for use.

Figure 4 is a perspective view of the coacting locking side rails of the wrapper pad.

Figure 5 is an enlarged detail transverse sectional view through one of the locking side rails.

Figure 6 is an enlarged detail sectional elevational view illustrating the function of the sealing flaps relative to the respective side rails of the wrapper pad.

Referring to the drawing by reference characters, the numeral 39 designates my improved wrapper pad in its entirety. The wrapper pad 39 comprises a flexible rectangular shaped body 40 which body includes an outer layer of paper 41, an intermediate layer of foil 42 and an inner paper lining 43. These several layers or plies of material are secured together inwardly of but adjacent their opposed longitudinal side edges by side rails 44 and 45 respectively. Each of the rails 44 and 45 is constructed of light channel metal and the wrapper pad body 40 adjacent its side longitudinal edges is folded into the channel of the side rails and the opposite walls of the side rails pressed inwardly to tightly grip the folded portions of the wrapper body. In order to facilitate inward bending of the sides of the

channel rails, the bight portion adjacent the opposite ends are notched or cut away as at 46. It is not necessary to press the entire length of the channel rails together for I have found that by pressing those portions adjacent the notches together is sufficient to tightly grip the folded portion of the wrapper body. By applying the side rails 44 and 45 to portions of the wrapper body adjacent its longitudinal side edges, I provide flaps 46—46 which are adapted to overlie the inner sides of the channel rails to protect the hair from contact therewith and to seal the joint between the side rails as illustrated in Figure 6 of the drawing when the wrapper pad is applied about the wound strand of hair.

The opposite ends of the channel rail 44 are pressed together and pivotally support locking bails 47—47 which receive the pressed extending ends 48 of the channel rail 45 when the wrapper pad is in use for the purpose of connecting the side rails together to prevent accidental unwinding of the wrapper body.

Secured to the inside of the wrapper body 40 as at 49 is a felt absorbent pad 50 which may be treated with a chemical solution such as is used in the art of permanent waving. The pad 50 lies within the wrapper body 40 and is protected by the wrapper body 40 as shown in Figure 3 when the wrapper pad is in use. After the strand of hair A shown in Figure 6 is fully wound upon the usual curling rod during one of the steps of a hair waving operation, the wrapper pad 39 is applied over the wound hair and curling rod and rolled to bring the longitudinal edges of the wrapper body together, after which the locking bails 47 are engaged with the extension portions 48 of the rail 45, the base of the strand of hair passing between the rails 44 and 45 as illustrated in Figure 6. The free end edges of the wrapper body 39 may be folded inwardly after the side rails have been locked together for the purpose of closing the ends of the wrapper. The inherent characteristics of the foil layer 42 will tend to maintain the ends of the rolled wrapper when folded inwardly.

Having thus described the invention, what I claim as new and desire to secure by Letters Patent of the United States, is:—

1. A wrapper pad for enclosing a wound strand of hair during a permanent hair waving process comprising a flexible rectangular shape wrapper body, an absorbent pad secured to said wrapper body for infolding therein, parallel side rails along opposite sides of said wrapper body and projecting from opposite ends thereof, and means

for securing the projecting ends of the side rails together when the wrapper body is rolled into tubular formation around a wound strand of hair to be waved.

5. 2. A wrapper pad for enclosing a wound strand of hair during a permanent waving process comprising a flexible rectangular shape body, a pair of channel side rails having their open sides facing inwardly toward each other and receiving the respective longitudinal side edges of said body, and channel rails having their opposed walls tightly embracing the edges of said body to be carried thereby, an absorbent pad on the inner side of said body, and means for securing said channel rails together at their ends when the wrapper pad is rolled into tubular formation about the wound hair to be waved.

3. A wrapper pad for enclosing a wound strand of hair during a permanent waving process comprising a pair of spaced parallel longitudinal side channel rails having their open sides facing toward each other, a flexible rectangular shape wrapper body having infolded longitudinal protecting flaps, the fold portions of said flaps being seated in the respective channel rails and tightly embraced thereby, an absorbent pad secured to the inner side of said body, and coacting means on the ends of said channel rails for securing the wrapper pad in rolled tubular formation when applied to a wound strand of hair to be waved with the protecting flaps overlapping the inner sides of the respective channel rails.

4. A wrapper pad for use in forming permanent waves in the human hair comprising a flexible rectangular shaped body, channel rails se-

cured to said body adjacent the respective longitudinal side edges thereof and disposed in parallel relation, the ends of said channel rails extending beyond opposite ends of said body, an absorbent pad secured to the inner side of said body, and coacting means on the projecting ends of said channel rails for securing the wrapper pad in a rolled tubular formation.

5. A wrapper pad for use in forming permanent waves in the human hair comprising a flexible rectangular shaped body, channel rails secured to said body adjacent the respective longitudinal side edges thereof and disposed in parallel relation, the ends of said channel rails extending beyond opposite ends of said body, an absorbent pad secured to the inner side of said body, and pivoted bail elements carried by the ends of one of said channel rails for engagement with the respective projecting ends of the other channel rail.

6. A wrapper pad for enclosing a wound strand of hair during a permanent hair waving process comprising a flexible rectangular shaped wrapper body, an absorbent pad secured to said wrapper body for infolding therein, parallel rigid members secured to opposite longitudinal sides of said wrapper body and projecting beyond opposite ends thereof, and means carried by the projecting ends of one of said members adapted for coacting engagement with the respective projecting ends of the other of said members for securing said rubber body in rolled tubular formation around the wound strand of hair to be waved.

PLATON CONSTANTINE.
